UNITED STATES PATENT OFFICE

CHARLES P. TOLMAN, OF KEW GARDENS, NEW YORK, ASSIGNOR, BY MESNE ASSIGNMENTS, TO PETROLEUM CONVERSION CORPORATION, OF NEW YORK, N. Y.

APPARATUS FOR THE DISTILLATION OF SOLID MATERIALS

Application filed June 3, 1925. Serial No. 34,544.

In the patent to Knox 1,428,641, September 12, 1922, the use of heated hydrocarbon gases is disclosed for the heat treatment of hydrocarbon oils.

5 The present invention relates to an improved form of apparatus suitable for the heat treatment or so-called distillation of carbonaceous materials, such for example, as oil shale, coal, lignite and similar materials, by 10 means of heated hydrocarbon gases or gases derived therefrom. Such apparatus, however, is of utility for the stated purpose irrespective of the particular composition of the heat carrier gas used.

15 In the accompanying drawings, I have shown an improved form of apparatus suitable for carrying out my improved process. In said drawings, Figure 1 is an elevational view, partly in section, of one arrangement 20 of apparatus; Fig. 2 is a plan view of the apparatus shown in Fig. 1; Fig. 2^a is a cross section through one of the blast stoves taken on line a—a of Fig. 1; and Fig. 3 is an elevational view of a modified form of apparatus.

25 Briefly stated the apparatus consists of a regenerative heating element or other source of hydrocarbon gases heated to the requisite temperature, a suitable distillation chamber, suitable condensing means and preferably a 30 holder or reservoir for the gases utilized in the system. Means are also provided for accomplishing purging of the system at suitable points. The heating elements which I prefer to use are hot blast stoves of the type similar 35 to those used in the blast furnace art, although it is to be understood that other types of gas heating elements may be used.

Referring particularly to Figs. 1 and 2, 10 denotes one of a plurality of hot blast stoves. 40 These stoves are identical in construction so that a description of one will suffice for all of them. Stove 10 has a central duct 11 around which is arranged suitable checker-work 12 so as to provide a plurality of vertical passages or flues. The stove is heated 45 by means of one or more burners 13 at the bottom thereof, the products of combustion passing upwardly through duct 11 and downwardly through checkerwork 12, and are 50 vented through pipe 14 (see Fig. 2^a). The

gas to be heated enters through valved pipe 15 and leaves the stove through valved pipe 16.

The hot gases from one of the blast stoves are introduced into distillation chamber 20 through pipe 16. Previously the chamber 20 55 has been filled with the material undergoing heat treatment e. g., oil-shale which has been ground to a suitable degree of fineness. The vapors generated by the heating are led from chamber 20 through valved pipe 33 to condenser 22, the condensate therefrom collecting in receiver 23. The gases and uncon- 60 densed vapors from the condenser 22 are drawn through pipe 24 by means of pump 25 and are again fed to the stove 10 which is 65 being used for heating. A connection from receiver 23 to a gas receiver 26 is provided in the form of a pipe 27 provided with a relief valve 28, which is set to be operative when the pressure exceeds a predetermined value. 70

The construction of chamber 20 is apparent from Fig. 1. As shown, means are provided in the form of baffles 30 for insuring intimate contact between the more or less finely di- 75 vided material undergoing heat treatment and the heated gases.

In the illustrative form of Figs. 1 and 2, a plurality of distillation chamber designated 20, 20^a and 20^b are preferably provided in order that the chamber 20^a, for example, may 80 be charged while chamber 20 is running, whereas chamber 20^b may be discharged during the same operation. To insure continuous operation, three hot blast stoves, 10, 10^a and 10^b are provided, each of the stoves being 85 joined to its respective distillation chamber by valved conduits 16, 16^a, and 16^b. Chambers 20, 20^a and 20^b are, in turn, joined to a main 31 through valved pipes 32, 32^a and 32^b, re- 90 spectively, each of these pipes having a valve, as shown. Main 31 is connected with condenser 22 by means of pipe 33, and thus any one of the three distillation chambers 20, 20^a and 20^b may be placed in communication with condenser 22 to the exclusion of the other two. 95

Means are provided for purging the stoves and the distillation chambers. Steam main 35 is provided with a branch 36 connecting stoves 10, 10^a and 10^b and with a branch 37 connecting each of distillation chambers 20, 100

20^a and 20^b. The purge from the stoves may be removed either through main 38 or through chimney conduits 14, while that from the distillation chambers is taken off through main 39, both main 38 and 39 joining a conduit 40 leading to receiver 26. The valve connections from steam branch 36, I designate as 41, 41^a and 41^b, respectively, and the offtakes from the stoves to purge main 38 as 42, 42^a and 42^b, respectively. Similarly, 5 43, 43^a and 43^b designate the valved connections from steam branch 37 to the distillation chambers, while 44, 44^a and 44^b indicate the offtake connections from the chambers 10 to purge branch 39. Similar parallel connections are provided for the return pipe 24 returning gas to the stoves, these connections being valved and designated 15, 15^a and 15^b.

To explain the operation of the apparatus, let it be assumed that the plant has not been 20 operated and is about to be set in operation. It may be assumed that distillation chamber 20 has been charged and that the stove 10 is about to be brought up to temperature. 25 This being the initial operation, it will be necessary to purge the bulk of the air from the system. Accordingly, the connection 41 to steam line 36 is opened, and the appropriate valved connections manipulated so as 30 to connect stove 10, chamber 20, condenser 22, receiver 23, valves 46 and 47 being opened.

When the system has been adequately purged by this through-flow of steam, valves 35 46 and 47 are closed, as well as connection 41, admitting steam to the stove 10. It will be noted that in the subsequent operation purging will be done through valved connection 42, main 38 and conduit 40 to receiver 26 when gas is purged from the chamber. When 40 air is purged from the stove 10, it is vented through a valve 140 in chimney conduit 14, Fig. 2^a.

The stove is now brought up to temperature by means of burner 13, the heat of combustion being accumulated in the brick checkerwork of the stove. In the meantime, stoves 10^a and 10^b have been similarly purged and fired. Chambers 20^a and 20^b have been charged with the material to be treated, and 45 the respective charging openings have been closed. The burner 13 is now shut off and steam is admitted to the stove through valved connection 41. This steam passes through the stove and purges it of the products of 50 combustion which are exhausted through the chimney valve 140. Both this valve and valve 41 are then closed.

The system having been purged of air and 55 the stove purged of products of combustion, the latter is brought up to pressure either by admitting gas from receiver or from another source joined by valved connection 47 or by admitting a hydrocarbon material to the pipe 18 as described below. The material is fed 60 in until the gaseous products formed by the

action of the heated checkerwork attain the desired pressure. Valved connections 16 and 32 are now opened, whereupon the heated hydrocarbon gases are admitted to chamber 20 and the products of distillation therefrom 70 flow into condenser 22. The temperature of the gas may be suitably regulated by means of a valved by-pass joining branch gas conduit 15 with gas conduit 16, not shown. Upon 75 leaving the condenser, the liquid fractions are accumulated in receiving tank 23 and the gas, now cooled from its passage through the condenser, flows through pipe 24 to pump 25, whereby continuous circulation is maintained.

The pressure in the system can be increased as desired by admitting to the stove hydrocarbon materials such for example as the heavy oils which break down into gases and light vapors upon their coming into contact with the heated checker work of such stove, 80 due attention being given relief valve 28 in conduit 27. As the operation proceeds the store of heat in the stove 10 is progressively exhausted. Preferably the capacity of each stove is so chosen that the heat stored in stove 85 10, for example, will be reduced to an operating minimum when the treatment of charge in chamber 20 is completed. The available heat in stove 10 having been exhausted, stove 10^a, which in the meantime has been heated, 90 purged and charged with gas to the pressure of the system, is connected in circuit with chamber 20^a by opening valved connections 15^a and 16^a. The stove 10 is then cut out 95 of the circuit and it and chamber 20 are 100 purged of their contained gas by establishing through valved connection 44, communication with pipes 39 and 40 leading to receiver 25 and then toward the end of the operation, 105 opening steam valved connection 41. In this manner the gas contained in the stove and 110 distilling chamber at the end of the operation, is saved. Stove 10 is now cut off from chamber 20, the chimney valve opened and 115 reheating of the stove begun by starting 110 burner 13.

In the meantime, if treatment of the charge has been completed at the end of the cycle, the treated material is discharged from distilling chamber 20 and a fresh charge deposited therein. Preferably the valves in 115 connections 32, as well as valves 32^a and 32^b between the distilling chambers 20 and the main 31 are of the non-return type, permitting flow from the retort to the condenser, but not in the reverse direction. Therefore, such evolution of gas or vapor as may take place in the retort in virtue of the residual heat thereof, may pass freely to the condenser if such accumulation builds to a pressure in excess of the pressure of the system.

In this manner the various distilling chambers are successively charged and discharged and the corresponding hot blast stoves brought up to temperature cut in and cut out 120 125 130

whereby the system is made practically continuous.

In Fig. 3, I have illustrated a system wherein the distillation chambers may be discharged and charged without interrupting operation. As shown, a distilling chamber 200 is provided having in valved communication therewith a charging hopper 200^a and a discharging hopper 200^b, both of approximately the same capacity as chamber 200. A stove 100 supplies hot hydrocarbon gases through pipe 101 to chamber 200, the products therefrom passing to a condenser 202, communicating with which is a receiver 203. A steam pipe 204 supplies steam for purging to the bottom of chambers 200, 200^a and 200^b. Assuming the system to be in operation, and it is desired to remove treated material from chamber 200 (hopper 200^b being empty) the pressure between the hoppers 200 and 200^b is first equalized by admitting cold gas through valved connection 205 into hopper 200^b, whereupon valve A between the two chambers is opened allowing the charge to pass from chamber 200 to hopper 200^b. Valve A is now closed. Discharging hopper 200^b is now purged of gas by admitting steam from pipe 204 thereto through the valved connection shown, the purge passing through a pipe 206 to a receiver 207. The charge in hopper 200^b may now be removed from the system by opening valve B connected to said hopper. Previously receiving hopper 200^a has been filled with fresh material, purged of air and brought up to the pressure of the system by opening valved connection 208 leading from stove 100.

Gas and uncondensed vapors leaving condenser 202 pass back to stove 100 through a pipe 209 and pump 210. A relief valve 260 is provided in line 209. Ordinarily stove 100 is one of an interconnected plurality whereby a continuous supply of hot gases may be insured.

The foregoing system thus provides for heat treating solid carbonaceous substances by the use of heated hydrocarbon or hydrogen containing gases. It will be obvious that by suitably controlling conditions of temperature and pressure such heat treatment may be effective to produce a simple distillation with the minimum of cracking of the liberated hydrocarbons, or such heat treatment may be utilized to bring about a thorough cracking of such hydrocarbons. The importance of applying heat through the medium of heated hydrocarbon gases is even greater when solid materials, such as shale or oil sand, are treated, than when liquid hydrocarbons are being treated, because the disadvantages and difficulties encountered in the direct application of heat to such solids are greater than in the direct application of heat to liquids. The conduction of heat from the wall of a vessel through crushed shale or

sand, for example, is even poorer than the conduction of heat from such hot wall to liquid. It is further to be noted that the unevenness of contact of the material to be heated with the wall introduces a special problem in the treatment of shale or sand in the retort. If relatively high interior pressures are used, the danger of overheating areas of the wall not in contact with the charge is a factor such that the operator must choose between the danger of rupture of the retort on the one hand, and on the other hand, a temperature so low as to give limited output from the apparatus.

In my improved system on the other hand, no such problem is presented since the heat is applied on the same side of the vessel walls as the material undergoing treatment.

I claim:—

1. In an apparatus of the type described, a plurality of regenerative heating elements, a plurality of distillation chambers, a source of heat carrier gases including a receiver, means for admitting gases from said source to a given heating element, a gas take-off connection joining said heating elements in parallel connecting conduits whereby the interior of any given distillation chamber may be operatively connected to any given heating element, condensing means, means for joining any given distillation chamber to said condensing means, means for connecting said condensing means to said receiver whereby to collect the gases therefrom, means for purging each of said elements when connected to a given distillation chamber, whereby both said heating element and the distillation chamber connected therewith may be purged in the same operation, and means for conducting the purge to said receiver.

2. An apparatus according to claim 1 in which three heating elements and three distillation chambers are provided thereby permitting the operations of charging, distilling and discharging to take place simultaneously.

CHARLES P. TOLMAN.
